REMOVABLE PARTITION CARRIER FOR
BOTTLES

Abraham J. Perlman, Brooklyn, N. Y.

Application January 24, 1942, Serial No. 428,097

2 Claims. (Cl. 294—87)

The present invention is directed to bottle carriers, more particularly to a device for carrying a plurality of bottles such as those containing soft drinks.

It is customary, at the present time, to provide a set of bottles in a carrier consisting of cardboard so cut, folded and assembled that it is capable of holding, say, six bottles which are so secured in the carrier that the carrier must be torn in order to allow the removal of one or more bottles. As a result, the carrier is capable of but a single use.

The present invention is directed to a carrier for bottles, but to a different type of carrier wherein the device may be used over and over again.

In view of this, it is among the objects of the present invention to provide a bottle carrier which may be readily placed in position to carry a specified number of bottles firmly and without danger of being accidentally disengaged.

It is also among the objects of the present invention to provide a carrier which is not only removable, but which may act as a partition for the ordinary wooden or other case used for storing a set of bottles, as for example, a group of 24 in a single box.

The present invention is based upon a different principle from that upon which the cardboard carriers is founded. Instead of the bottles resting upon the carrier and being held in the same manner as in a box, the present invention provides means for gripping the necks of the bottles firmly and securely when desired, so that a group of bottles may be carried without danger of breakage.

In a specific embodiment of the invention, the carrier consists of a block which constitutes the body of the carrier and is formed along its side edges with recesses or openings which are semi-circular in cross-section. Hinged to the body along the opposite sides thereof, adjacent to said openings, is a pair of additional blocks having openings similar to those in the body and cooperating therewith, so that when the blocks are in a position touching the sides of the body, the sets of openings provide cylinders. These cylinders are of such size and shape as to hold within them the necks of the bottles to be carried.

Means are provided for carrying the assembly, 50 said means simultaneously constituting a lock which will prevent accidental movement of the side blocks and thus prevent slipping and breakage of bottles from the device. In one form of the invention, this means consists of cords which

have their ends fastened to the blocks, which are threaded through the blocks and the body, and so arranged that when the handle portion of the cords is grasped, the weight of the assembly will cause the blocks to grip against the body and firmly hold the bottles.

The size of the carrier is usually such that it is capable of holding six bottles in two rows of three each. Thereby, when a case of bottles is to 10 be provided, said case containing 24 bottles, four such carriers are assembled over the necks of the bottles, thus closing the open box and acting as a protection for the bottles while being transported and in storage. The use of such carriers eliminates the necessity for the partitions which are generally fixed in such boxes in order to keep the bottles from being thrown against each other. With the present invention, no such partitions are necessary, as the gripping of the necks of the 20 bottles by a properly designed carrier will firmly hold the bottles against breakage.

In the accompanying drawing constituting a part hereof and in which like reference characters indicate like parts:

25 Fig. 1 is an end view of the new bottle carrier showing the blocks in partly open position and their relation to the bottles;

Fig. 2 is a plan view looking up from beneath 30 the carrier, showing the arrangement and spacing of the bottle neck openings;

Fig. 3 is a cross-sectional view taken along the line 3—3 of Fig. 2;

Fig. 4 is a similar section taken along the line 4—4 of Fig. 2; and

Fig. 5 is a side view of the carrier.

The device consists essentially of a body 1 having openings 2 along one side thereof and similar openings 3 on the opposite side, the cross-section of each of the openings being semi-circular. A cover member 4 secured to the top of body 40 1 closes the top of the openings, and said cover may be made integral with the body.

A side block 5, having a series of semi-circular openings 6 in alignment with openings 2, is hinged to body 1 by plate-like members 7 at the ends thereof, the latter being secured to block 5 by rivets 8, and the opposite end being pivoted at 9 to body 1. A similar block 10, having a series of openings 11 which cooperate with openings 3, is placed at the opposite side of body 1 and is held thereto by members 12 which are riveted to the ends of block 10 as shown at 13 and is pivoted at 14 to body 1. Covers 15 close the upper portion of openings 6 and 11, and said covers may be made integral with blocks 5 and 10.

Within block 5 is an opening 16 communicating with an angular opening 17 in body 1, as shown in Fig. 3. The upper end of opening 17 extends through cover 4. Similarly, an opening 18 is provided in block 10 communicating with angular opening 19 in body 1, said opening extending through the cover of the body.

The set of openings illustrated in Fig. 3 is along the section line 3—3 of Fig. 2, at the left of said figure, and a duplicate set of openings is provided at the right hand side thereof. A cord has its ends 20 knotted as shown in Figs. 2 and 3 and is threaded through openings 16 and 17, emerging at 21 and forming one-half of a handle 22. Similarly, on the other side a cord has its ends knotted as shown at 23, passes through openings 18 and 19, emerging at 24 and forming the other half 25 of the handle.

In use, the device is placed over bottles 26 with the shoulders 27 of the openings against the necks of the bottles. The handles 22 and 25 are grasped, pulling up the cord and causing blocks 5 and 10 to move downwardly from the position shown in Fig. 1, and inwardly to grip the necks of the bottles. The handles 22 and 25, when held by the user, will continue to exert pressure upon the necks of the bottles and thus firmly hold the same in place.

Although I have described my invention setting forth a single embodiment thereof, my invention is not limited to the details of construction, as various modifications are possible within the principles set forth. For instance, although usually the carrier is made of wooden members, it may be made of other materials such as fiber, metal, plastic or combinations of various materials. The openings in the several parts are shown as extended only partly through the members themselves, so that the top of the carrier is closed. However, it is possible to provide open-

ings going all the way through the members so that the bottle caps will be visible from above.

The above illustrates the fact that many variations in actual construction may be made and that the invention is broader than the single specific embodiment. Therefore, the invention is to be broadly construed and not to be limited except by the character of the claims appended hereto.

Instead of hinges for pivoting the blocks to the body, pins may be provided extending out of the faces of the body and into recesses in the adjacent blocks, or vice versa, whereby a sliding movement is imparted to the blocks instead of arcuate.

What is claimed is:

1. A bottle carrier comprising a body block, a pair of additional blocks at opposite sides of said body block and pivoted thereto by sets of hinges, cooperative openings in said body block and said additional blocks adapted to surround the neck of a bottle therebetween, and means for holding said additional blocks against said body block to grip said bottles, said means including cords having the ends secured in said additional blocks, the cords passing through the sides of said body block and out through the top to provide a carrier handle.

2. A bottle carrier comprising a body block, a pair of additional blocks at opposite sides of said body block and pivoted thereto by sets of hinges, cooperative openings in said body block and said additional blocks adapted to surround the neck of a bottle therebetween, and means for holding said additional blocks against said body block to grip said bottles, the pivot points being on said body block at a substantial distance from the additional blocks to provide lever arms for said additional blocks.
